(57) CLAIM

I claim the ornamental design for a pet food and accessory holder, as shown and described.

DESCRIPTION

FIG. 1 is top perspective view of the pet food and accessory holder; and

FIG. 2 is a front view thereof; and

FIG. 3 is a rear view thereof; and

FIG. 4 is a left side view thereof; and

FIG. 5 is a right side view thereof; and,

FIG. 6 is a top view thereof.
